BABY SEAT ATTACHMENT FOR SHOPPING CARTS

Donald Gugler, 10208 Swinton Ave.,
Los Angeles, Calif. 91343

Filed Dec. 11, 1969, Ser. No. 20,451

Term of patent 14 years

Int. Cl. D12—02; D6—01

U.S. Cl. D14—3

FIG. 1 is a perspective view of a baby seat attachment for shopping carts, showing my new design;

FIG. 2 is a side elevational view thereof;

FIG. 3 is a front elevational view thereof;

FIG. 4 is a rear elevational view thereof; and

FIG. 5 is a top plan view thereof.

I claim:

The ornamental design for a baby seat attachment for shopping carts, substantially as shown.
